COMBINED STEERING WHEEL AND COVER

Chris G. Nicozisis, 15378 Ardmore, Detroit, Mich.

Filed Oct. 15, 1959, Ser. No. 57,949

Term of patent 14 years

(Cl. D14—30)

FIG. 1 is a plan view of a combined steering wheel and cover showing my new design.

FIG. 2 is a sectional view taken along the line 2—2 in FIG. 1.

FIG. 3 is a sectional view taken along the line 3—3 in FIG. 1.

FIG. 4 is a fragmentary sectional view taken along the line 4—4 in FIG. 1.

FIG. 5 is a fragmentary elevational view taken in the direction of the arrow 5 in FIG. 1.

The dominant features of my design reside in the portions shown in full lines. The shading in FIGS. 1 and 5 denotes contrasting colored areas.

I claim:

The ornamental design for a combined steering wheel and cover, as shown and described.
